UNITED STATES PATENT OFFICE.

HENRY F. BECHMAN, OF BATTLECREEK, MICHIGAN, ASSIGNOR TO THE DUPLEX PRINTING PRESS COMPANY, OF BATTLECREEK, MICHIGAN.

FLAT-BED WEB-PRINTING PRESS.

No. 809,241.

Specification of Letters Patent.

Patented Jan. 2, 1906.

Application filed February 11, 1905. Serial No. 245,228.

To all whom it may concern:

Be it known that I, HENRY F. BECHMAN, of Battlecreek, in the county of Calhoun and State of Michigan, have invented certain new and useful Improvements in Flat-Bed Web-Printing Presses; and I hereby declare that the following is a full, clear, and exact description thereof, reference being had to the accompanying drawings, which form 5 part of this specification.

This invention is an improvement in flat-bed web-printing presses of the "duplex" type; and its object is to provide an attachment for such press whereby additional impressions may be made upon such attachment, consisting of a supplemental printing mechanism preferably located between the first and second or upper and lower beds, the portion of the web in the duplex press at this 15 point being momentarily stopped during the time that the cylinders are making impressions thereon from the type-forms on the beds. By means of this attachment third 20 impressions in color may be made upon the web, so as to impart a striking or distinctive 25 appearance to portions of the completed papers. No additional web guiding or feeding mechanisms are required, and this supplemental printing mechanism can be operated 30 directly from the operative parts of the ordinary duplex press.

The invention is shown in the drawings as applied to an ordinary duplex flat-bed web-perfected press, but of course is applicable 35 to other flat-bed web-printing presses. I therefore do not wish to restrict the invention to the specific form of press indicated in the drawings.

In the accompanying drawings, Figure 1 is 40 a diagrammatical view of a duplex press, indicating a longitudinal section therethrough and showing my attachment connected thereto. Fig. 2 is a detail.

In the drawings, *h* and *h'* represent the stationary type-beds, over which are reciprocated the cylinders *H* and *H'*, which are reciprocated back and forth over said beds by a suitable mechanism, as in the well-known *x* press. The web *w* is led in from the *t* one end of the press, through the in- 5 K, under a suitable guide-roller, *l*, down under a guide *M*, then the bed *h* and cylinder *H*, guide *m*, up over the upper

guide *m'*, back between the bed *h'* and cylinder *H'*, to and over the guide *M*, down under the upper looping-roll *l'*, then to the delivery-rolls *O*, from whence it passes to the folder. The looping-rollers *l* *l'* are connected by a rod *L*, attached to a lever *A*, actuated by a 60 cam *D* on a transverse shaft *E*, which is geared to the main driving-shaft of the machine. All of the aforesaid parts are well known and need no further description, and their operation is fully described in the patent 65 to Cox, No. 501,456, granted July 11, 1893, and No. 478,503, of July 5, 1892.

The portion of the web *w* passing over the rollers *m* *m'* at the rear end of the machine is momentarily stopped during the time the cylinders *H* *H'* are impressing the web upon the type-form on beds *h* *h'*, and my printing attachment is preferably located at this point. It comprises a platen 2, which is located between the rolls *m* *m'* in such position that the web *w*, moving between said rolls, passes over the face of the platen. Opposite this platen is a movable bed or type-carrier 3, which is supported on oscillating lever or levers *3^a*, pivoted at *3^b* on a suitable support 70 attached to the main frame of the press. Said levers are adapted to be oscillated to move the carrier toward and from the platen 75 2. The type-carrier 3 may be arranged like the bed of an ordinary platen-press and is 80 adapted to carry a type-form, which can imprint the web against the platen 2 while the web is momentarily stationary between the rollers *m* *m'*. Any suitable mechanism may be provided for inking the type on this carrier 3; but as this inking mechanism forms 85 no part of my present invention I have not shown the same detailed herein, the inking-rollers being merely indicated at *3^c*. The lower end of the lever *3^a* below the pivot *3^b* 90 is connected to a reciprocating bar 4, the end of which may pass loosely through an opening *3^d* in the lower end of lever *3^a*, and the bar is held engaged with the lever by means of a collar *4^a* on the outer end of the 95 bar and by means of a spring *4^b*, interposed between the end of the lever and a collar *4^c* on the bar 4. The bar 4 extends backward through suitable supports and guides *4^e* and under bed *h* toward the shaft *E* and on its 100 inner or rear end is provided with rollers *4^f*, which engage cam-grooves *5^a* in cams 5, attached to the shaft *E*, which operates the 105

looping mechanism. The cams 5 are adapted to impart one reciprocatory movement to the lever E for each revolution of the shaft E, which shaft rotates once for each printing 5 stroke of the cylinders H H' over the beds h h', and the cam 5 is so formed and timed that the type-carrier 3 is moved toward the platen during the time the cylinders H H' are operating upon the beds and while the 10 web is momentarily stopped between the rollers m m'. Thus the type-carrier will make imprints upon this portion of the web while the impressions are being made thereon on beds h h'. The type-carrier is retracted out of the way before the web w is shifted.

From the foregoing it is obvious that this attachment can be applied to duplex presses already in the field as well as to new presses 20 and that it involves no addition or complication of the web-feeding mechanism of such machines nor any alteration in the operation of the web in such press. The supplemental printing mechanism can be used for making 25 colored impressions on the web or for addressing the papers and for other purposes, such as making colored inserts and where it is desired to especially call attention to any particular matter appearing in the paper.

30 Having thus described my invention, what I claim as new, and desire to secure by Letters Patent, is—

1. The combination with a flat-bed web-perfecting press having two separated printing - couples, of a supplemental printing mechanism arranged to operate upon the web at a point intermediate the first and second printing mechanism.

2. The combination with a press having a 40 plurality of separated printing mechanisms each comprising a bed and coacting cylinder adapted to successively print a web, of a supplemental printing device adapted to operate upon the web intermediate the said printing mechanisms.

3. The combination with a web-perfecting press having a plurality of separated printing mechanisms each comprising a coacting bed and cylinder, of a supplemental printing mechanism comprising a platen and a reciprocating bed, and arranged to operate upon the part of the web intermediate the first-mentioned printing mechanisms.

4. The combination of a web - perfecting 55 press having a pair of stationary beds and reciprocating cylinders adapted to perfect the web; with a platen-press arranged intermediate the first and second beds and cylinders, and adapted to operate upon the portion of the web intermediate said beds and cylinders.

5. The combination with a flat-bed web-perfecting press, comprising a pair of separated stationary beds and coacting cylinders 60 adapted to successively operate upon the

web, of a supplemental printing mechanism, comprising a platen and a reciprocating type-carrier, arranged to operate upon the portion of the web intermediate the first and second impression-cylinders.

6. In combination with a duplex flat-bed web-perfecting press having a pair of parallel beds, a pair of reciprocating cylinders respectively coacting with said beds and means for feeding the web of paper successively between the beds and cylinders to be perfected thereby, of a reciprocating printing mechanism at one end of the beds adapted to operate upon the portion of the web between the first and second cylinders.

7. The combination with a duplex press having a pair of stationary beds and coacting cylinders, means for continuously feeding the web to and from said press, means for directing the web successively between the 85 beds and cylinders to be perfected thereby and means for intermittently moving the intermediate part of the web through the printing mechanism; of a third printing mechanism located at a point intermediate the first 90 and second type-beds and adapted to operate upon the intermediate part of the web while it is momentarily stationary.

8. The combination of a stationary bed, a reciprocating cylinder, means for feeding the 95 web continuously to and from the press, and a pair of devices for looping the web between the feed and delivery and whereby it may be intermittently shifted over the bed; with a supplemental printing mechanism arranged 100 to operate upon the web at a point intermediate the looping devices.

9. The combination of a stationary bed, a reciprocating cylinder, means for feeding the web continuously to and from the press, and 105 two separated devices for looping the web between the feed and delivery, and whereby it may be intermittently shifted over the bed; with a stationary bed and a reciprocating type-carrier arranged to operate upon the 110 web at a point intermediate the looping devices, and a cam operated by the looping cam-shaft for actuating said type-carrier.

10. The combination with a press comprising upper and lower stationary type-beds, 115 a pair of reciprocating cylinders respectively coacting with said type-beds, web-guiding mechanism for directing a web successively between the beds and cylinders, means for feeding the web to and from the press, and 120 mechanism for looping the web to shift a portion thereof intermittently between the beds and cylinders, of a stationary platen and reciprocating type-carrier located in the 125 of the web intermediate the first and second cylinders, and a reciprocating bar 130 with the reciprocating type-carrier arranged to operate the latter when the web in the press is stationary.

11. The combination with a press comprising upper and lower stationary type-beds, a pair of reciprocating cylinders respectively coacting with said type-beds, web-guiding mechanism for directing a web successively between the beds and cylinders, means for feeding the web to and from the press, devices for looping the web to shift a portion thereof intermittently between the beds and cylinders, and a shaft and cams for operating the looping devices; of a stationary platen and a reciprocating type-carrier, located in

the path of the web intermediate the first and second cylinders, a reciprocating bar connected with the reciprocating type-carrier, and cams on the said shaft adapted to operate the bar, substantially as described. 15

In testimony that I claim the foregoing as my own I affix my signature in presence of two witnesses.

HENRY F. BECHMAN.
